UNITED STATES PATENT OFFICE.

FRANK CRAWFORD, OF NEW BRUNSWICK, NEW JERSEY, ASSIGNOR OF
ONE-HALF TO ALFRED MARCH, OF SAME PLACE.

STOP MECHANISM FOR KNITTING-MACHINES.

SPECIFICATION forming part of Letters Patent No. 445,465, dated January 27, 1891.

Application filed June 28, 1890. Serial No. 357,124. (No model.)

To all whom it may concern:

Be it known that I, FRANK CRAWFORD, a citizen of the United States, residing at New Brunswick, in the county of Middlesex and State of New Jersey, have invented new and useful Improvements in Stop Mechanism for Knitting-Machines, &c., of which the following is a specification.

This invention relates to a stop mechanism 10 of the kind employed in knitting-machines; and the invention consists in the details of construction set forth in the following specification and claims, and illustrated in the accompanying drawings, in which—

15 Figure 1 is a side elevation, partly in section, of stop mechanism containing my invention. Fig. 2 is a plan view of Fig. 1, partly broken away. Fig. 3 is a section along line $x\ x'$, Fig. 2. Fig. 4 is a detail view of a slide 20 and adjacent parts. Fig. 5 is a detail inverted plan view of a disk. Fig. 6 is a detail view of a finger. Fig. 7 is a view, partly in section, along line $x'\ x'$, Fig. 6. Fig. 8 is a detail view showing the belt-shifter when released. Fig. 25 9 is a section along line $y\ y'$, Fig. 1. Fig. 10 is a section along line $z\ z'$, Fig. 1.

In the drawings, the letter A indicates a suitable stem or support carrying a guide or rim B, having suitable eyes C D for guiding 30 the thread E to the work. In passing to the work the thread passes through the eye F of a finger G, and as long as said thread is stretched through the finger-eye F said finger is held up in the position shown in Fig. 35 1. The breaking of the thread allows the finger G to drop, and thereby stop the machine, as will be set forth.

The finger G is secured to a pin or axle H, extending through a suitable eye in the rim 40 I of the plate K, secured to the stem A. The inner end of the axle H is bent or provided with a stud L. When the finger drops, said stud L strikes against a shoulder M, formed on a lever or disk N, fulcrumed or pivoted at O. The disk N is shown as having several shoulders M, adapted for a corresponding 45 number of fingers G, according as more or less threads are employed. If only one thread should be employed, only one finger G and 50 one shoulder M are necessary, in which case the disk N, with its various shoulders M, might

be replaced by a lever or arm having but one shoulder and fulcrumed at O. The fulcrum O is readily formed by a stud entering a suitable eye in the plate K. The lever or disk N 55 has a stud P, entering a fork Q, secured to the slide R, whereby the lever or disk may be oscillated and set by moving the slide back and forth. A spring S tends to force the slide toward the stop T. A lever or arm U, fulcrumed 60 at V, is connected by a pin-and-slot connection WX to the slide R. The lever U has a stud or projection Y, and when the slide R is drawn away from stop T the lever U is moved so as to swing its stud Y toward the 65 detent or catch Z, fulcrumed or pivoted at a. A spring b presses on the catch Z.

When the stud Y is swung toward the catch Z, said stud rides along the inclined face c of the catch and passes into the locking recess 70 or shoulder d in said catch, the spring b allowing the catch to yield sufficiently for the stud Y to enter the recess d, after which the spring b forces the catch back to its locking position, so as to hold the stud in said recess. 75 The lever U and slide R are thus held against the action of spring S, so that the slide R rests away from the stop T, Fig. 2. When, now, the thread E breaks or runs out, the finger G drops, thereby causing its stud L to 80 strike against a shoulder M, so as to move the arm or disk N and force the stud P against the tail e of catch Z, whereby the catch is forced to its releasing position against the pressure of spring b and the stud Y is released, whereupon the lever U and slide R are 85 moved by spring S, so that the slide R comes to rest against the stop T, Fig. 4.

To the slide R is connected an arm f, extending from the pivot g, which is provided 90 with a finger h. Another finger i extends from the pivot k, carrying a detent or hook l. A spring m tends to force the detent l to its engaging position. A lever n, fulcrumed at o, has a stud p, adapted to be engaged by the 95 detent l. The lever n is connected by a pin-and-slot connection qr to the belt-shifter or belt-shifting slide s. A spring t tends to force the belt-shifter to the releasing position, so as to force the belt out of work. 100

When the finger G drops, the slide R, as already stated, is moved against the stop T,

- thereby causing the slide to move the arm *f*, so that the finger *h* strikes against finger *i* and moves the detent *l* to its releasing position against the pressure of spring *m*. The 5 stud *p* is thus released, so that the lever *n* and belt-shifter *s* are moved by the spring *t* to throw the belt out of work, Fig. 8. When the finger *G* is again threaded and held up, the slide *R* can again be set away from stop 10 *T*, whereby the finger *h* releases finger *i*, and the detent *l* is moved by its spring *m* back to its engaging position. As long as the finger *G* is not threaded and held up, said finger will 15 continue to force the stud *P* against the tail *e* of catch *Z*, so as to hold the catch in its releasing position and make it impossible for the slide *R* to be set away from the stop *T* and the finger *h* to be set so as to release the finger *i* and detent *l*. The belt-shifter *s* can 20 thus not be set back, and the machine cannot be started until the finger *G* is threaded and held up.
- The stem *A*, as seen, need not pass through the center of the plate *K*, but to one side of 25 the center. In that case the axles *H* of the fingers, instead of passing only through the rim *I*, may in some cases be lengthened, so as to pass through said rim and also through arms *u*, extending at different lengths from said 30 rim, so as to compensate for the eccentricity of the plate *K* and bring the various fingers *G* into position to be engaged by their respective threads as they pass through the various eyes *C D*.
- 35 The connection between the fingers *G* and axle *H* is readily formed by bending the end of the finger into a coil *v*, sitting about the axle, and providing the axle with a slot *w*, into which the finger *G* springs, so as to lock 40 the axle and finger together.
- What I claim as new, and desire to secure by Letters Patent, is—
1. The combination, with a belt-shifter and a detent for said shifter, of a spring-actuated 45 releasing slide or actuator *R*, intermediate devices operatively connecting the detent with the slide or actuator, a locking arm or lever *U*, connected to said slide, a catch or

detent for said locking-arm, a releasing disk or lever *N*, made to act on said catch, and a 50 finger *G* for actuating said disk or lever, substantially as described.

2. The combination, with a belt-shifter and a detent for said shifter, of a spring-actuated slide or actuator *R*, a finger *h*, devices connecting the latter with the slide or actuator, a finger *i*, connected to the shifter-detent and actuated by said finger *h*, a locking arm or lever *U*, connected to said slide, a catch for said locking-arm, a releasing disk or lever *N*, made to act 55 on said catch, and a finger *G* for actuating said disk or lever, substantially as described.

3. The combination, with a belt-shifter and a detent for said shifter, of a spring-actuated 60 slide or actuator *R*, intermediate devices operatively connecting the detent with the slide or actuator, a locking arm or lever *U*, connected to said slide, a catch for said locking-arm, a releasing disk or lever *N*, made to act 65 on said catch, a fork *Q* and stud *P* for connecting the slide *R* and disk or lever *N*, and a finger *G* for actuating said disk or lever, substantially as described.

4. In a stop mechanism, the combination, 70 with the spring-pressed slide or actuator *R*, of a slide-locking lever *U*, a spring-pressed catch or detent *Z* for holding the lever to lock the slide, the releasing-fingers *G*, and devices intermediate the catch or detent and the fingers for causing the latter to actuate the catch or detent and release the locking-lever, substantially as described.

5. A releasing-finger for a stop mechanism, 75 said finger consisting of a wire stem having its end formed into a coil, in combination with an axle *H*, made to enter said coil and provided with a notch for the engagement of the stem or finger, substantially as described.

In testimony whereof I have hereunto set 80 my hand in the presence of two subscribing witnesses.

FRANK CRAWFORD.
